UNITED STATES PATENT OFFICE.

JASON H. GREENSTREET, OF INDIANAPOLIS, INDIANA.

BOX-BLANK AND BOX.

1,280,718.

Specification of Letters Patent.

Patented Oct. 8, 1918.

Application filed December 15, 1915. Serial No. 66,924.

To all whom it may concern:

Be it known that I, JASON H. GREENSTREET, a citizen of the United States, residing at Indianapolis, in the county of Marion and State of Indiana, have invented a new and useful Box-Blank and Box, of which the following is a specification.

The object of my invention is to produce a blank, or a series of blanks, comprising 10 a main body sheet of flexible material, such, for instance, as the material commonly known in the market as fiber board, and cleats, from which a foldable box blank of desired dimensions may be produced by 15 the assembly of the required number of individual sections, the assembly resulting in a stiffening or reinforcement of the longitudinal corners of the completed box.

The accompanying drawings illustrate 20 my invention. Figure 1 is a perspective view of the completed box; Fig. 2 a transverse section, in a plane parallel with the removable ends, the end sheet being broken away at its corners to show the relation of 25 the several cleats; Fig. 3 a plan of a series of four separate sections prior to their assemblage in foldable-blank form; Fig. 4 a similar view showing the sections fastened together and one series of cleats turned up 30 into foldable relationship; Fig. 5 a section, on a larger scale, on line 5, 5 of Fig. 4; Fig. 6 a perspective view of a slightly modified form of completed package, the portions of the sheets being broken away to 35 show parts which would be otherwise hidden; Fig. 7 a fragmentary section of the modification shown in Fig. 6; and Fig. 8 a plan of a slightly modified box-forming section embodying my invention.

40 In the drawings, 10 indicates the main sheet of one of my box sections of material which is capable of being bent along desired fold lines, such, for instance, as fiber board, corrugated board, other suitable paper products, etc. The size of each sheet 45 10 will be determined by the dimensions of the box desired and at each side edge it will be provided with a flap 11, a fold line 12 being formed, by scoring, pressing or otherwise, to facilitate, if that is necessary, the folding of the flaps 11 to positions at 50 an angle to sheet 10. Two cleats 13, 13 are attached to sheet 10 in such manner that, when several sections are brought together 55 and folded, the said cleats will interengage

to form stiffening frames for the ends of the box. In all of the figures of the drawings except Fig. 8, these cleats are shown attached to the sheet 10 in a manner shown in my Patent No. 1,032,539, the sheet 10 being provided at its ends with flaps 14 to which the cleats 13 are attached and then folded along the fold lines 15 until they come into proper blank-folding position, as shown in the lower part of Fig. 4. If those flaps 11 which are to ultimately lie within the completed package are long enough to project into the final plane of the cleats so as to be overlapped by said cleats, the cleats should be attached to the flaps 14 at a distance from the fold line 15 equal to the thickness of the material of the sheet 10, as indicated in Fig. 3. Those side flaps 11 which are to lie outside of the completed package may conveniently be made of a length substantially equal to the length of the body sheet 10, as indicated in connection with the top and bottom sections of the series shown in Figs. 3 and 4.

The top, bottom and side sections are 60 formed independently and may, therefore, be produced in stock dimensions so that by proper selection of stock sections, boxes of any standard dimensions may be produced. The several sections are brought together in 65 the manner shown in Fig. 4, the body sheets 10 and flaps 11 being overlapped, as indicated, and the externally-lying flaps 11 are attached to the body sheets of the adjacent sections in any suitable manner. They may 70 be glued or they may be attached by fastening members, such as staples 16. The internally-lying flaps 11 may also be attached to the main body of the adjacent section, but in that case special scoring at the fold line 75 of the internally-lying flap 11 must be resorted to in order to compensate for the thickness of the material at the fold line or corner of the completed package.

The production of the individual box-forming sections considerably facilitates manufacture and ultimate production of packages of various sizes, and the overlapping of the flaps 11 upon the adjacent bodies 10 produces a double thickness of material 100 at the longitudinal edges of the package between the cleat planes, thus materially stiffening the package in lines at right angles to the end planes not only against thrusts along those lines, but also against 110

tearing stresses resulting from a racking of the package.

Any suitable form of ends may be used and in the drawings I have shown an end 5 consisting of a sheet 20 of the same material as the body members, provided with a pair of transverse cleats 21, each having tongues 22 at their ends, said tongues projecting into mortises 23 formed in the cleats 10 13 of the side members, said mortises being sufficiently deepened for that purpose.

By making those flaps 11 which lie within the package of sufficient length to be overlaid by the cleats when said cleats are folded 15 into blank-folding position, as indicated at the right of Fig. 5, the cleats serve to hold the ends of said interior flaps 11 firmly in place and this serves to assist in the stiffening effect of these flaps upon the box corner.

20 In the form shown in Fig. 8, the end flaps 14 are omitted and the cleats 13 are applied directly to the main body sheet 10'. In this form, the side flaps 11' which are intended to lie within the package, must be 25 made short enough to lie between the cleats when the parts are brought together in box blank arrangement.

The top section will, of course, have a side flap along that edge which forms the 30 free edge of the cover. This final flap 11^a may lie outside of the adjacent side member, as shown in Fig. 1, being attached thereto by any suitable means to hold the box closed, but for some packages it will be 35 advisable to protect this flap, and for that purpose a strip 25 may be applied to the outer face at the top edge of the front section so as to form a pocket 26 for the reception of the flap 11^a (Fig. 6), the flap 11 40 at the top of the front section extending horizontally beneath the main body of the top section when the top is folded into closed position. Instead of using the strip 25, a pocket for the flap 11^a may be formed 45 in the manner shown in Fig. 7, a strip 27 being applied to the inner face of the sheet 10 of the front member of the box. In this case, the upper edge of this front member will not be provided with any edge flap, 50 but, instead, the strip 27 will be of such width as to extend beyond the edge of said sheet 10, thus forming a flap 28 which will extend beneath the main body of the top section.

Copies of this patent may be obtained for five cents each, by addressing the "Commissioner of Patents, Washington, D. C."

I claim as my invention:

55

1. A foldable box blank comprising a plurality of individual sections, each formed of flexible sheet material and transverse cleats, each of said sections having edge flaps overlapping the body sheet of an adjacent section, and one of said overlapping flaps adjacent each fold line being secured to the overlapped body. 60

2. A foldable box blank comprising a plurality of sections, each section comprising a main body sheet, edge flaps overlapping the main body sheet of an adjacent section, one edge flap at each fold line being attached to the adjacent body sheet, end flaps foldable with relation to the body sheet, 70 and cleats attached to said end flaps and extending transversely with relation to the side flaps. 75

3. As an article of manufacture, a box blank section comprising a main body sheet 80 of flexible material having side flaps foldable with relation to the body sheet, and also having end flaps foldable with relation to the body sheet, and cleats attached to said end flaps. 85

4. A foldable box blank comprising a plurality of sections, each section comprising a main body sheet, edge flaps overlapping the main body sheet of an adjacent section, one edge flap at each fold line being attached to the adjacent body sheet, end flaps foldable with relation to the body sheet, 90 cleats attached to said end flaps and extending transversely with relation to the side flaps, and a flap-receiving pocket carried by one of the terminal sections of the blank to receive the side flap of the free edge of the other terminal section. 95

5. A foldable box blank comprising a plurality of body sections, each section comprising a main portion and edge flaps foldable relative to the main body and an edge flap at each fold line overlapping an adjacent body sheet and attached thereto, and cleats attached to said body sheets in position to coöperate in series when the blank is folded into box form. 100

In witness whereof, I have hereunto set my hand at Indianapolis, Indiana, this thirteenth day of December, A. D. one thousand nine hundred and fifteen. 105

JASON H. GREENSTREET.
